A. BLISSMAN & R. E. STRUSE,
PORTABLE DRAIN BOARD.
APPLICATION FILED OCT. 8, 1915.

1,224,838.

Patented May 1, 1917.

UNITED STATES PATENT OFFICE.

AMOS BLISSMAN AND RICHARD E. STRUSE, OF NEW YORK, N. Y.; SAID BLISSMAN
ASSIGNOR TO SAID STRUSE.

PORTABLE DRAIN-BOARD.

1,224,838.

Specification of Letters Patent.

Patented May 1, 1917.

Application filed October 8, 1915. Serial No. 54,816.

To all whom it may concern:

Be it known that we, AMOS BLISSMAN and RICHARD E. STRUSE, citizens of the United States, residing at New York, in the county 5 of Bronx and State of New York, have invented new and useful Improvements in Portable Drain-Boards, of which the following is a specification.

This invention relates to a portable drain 10 board preferably formed from a single sheet of material and which may be used in connection with stationary wash tubs or the like.

The primary object of the invention is to 15 provide a board of the class described which may be formed of comparatively light material and shaped in such a manner that water from articles placed upon the drain board will be directed into a waste receptacle.

A further object of the invention is to 20 provide a board of the character described with an upstanding and rolled flange upon three sides thereof which affords a hand hold 25 when lifting the device.

A still further object of the invention is to 30 provide a drain board with grooves in the bottom thereof, arranged in such a manner that they coöperate with the upstanding flange upon three sides of the board to prevent the sagging of the board from the 35 weight of articles placed thereon and thus prevents the cracking of the enamel with which the board may be coated if found desirable.

A final and important object of the invention is to provide the drain board with feet depending from its rear end and a spout depending farther from its front end so 40 that, when this spout overhangs the sink the bottom of the drain board is pitched in one direction, but when the device is removed and laid upon a flat support the spout raises this end of the drain board and causes its 45 bottom to incline in the opposite direction whereby water is trapped therein rather than permitted to run out.

With these and other objects in view the invention resides in the construction and arrangement of different portions of the board set forth in the following specification and falling within the scope of the appended 50 claim.

Figure 1 is a perspective view of the improved drain board showing the same rest-

ing upon a cover on a stationary wash tub and arranged with the deflected portion of the drain board superimposed above a sink.

Fig. 2 is a vertical longitudinal sectional view taken on the line 2—2 of Fig. 1. 60

Fig. 3 is a cross section on the line 3—3 of Fig. 1.

Fig. 4 is a top plan view of the drain board removed from the cover of a stationary wash tub upon which it is shown 65 supported in Fig. 1 of the drawings.

Fig. 5 is a perspective view showing a modified form of the invention.

Like characters of reference denote corresponding parts throughout the several 70 views of the drawing.

The numeral 1 designates a set of wash tubs and 2 a sink which is usually located in close proximity to said tubs while the numeral 3 designates covers of the stationary 75 wash tubs upon which the improved drain board may be supported when in use.

The improved drain board is designated by the numeral 4 and comprises a grooved body 5 having an upstanding flange across 80 one end and above both sides thereof, as indicated by the numeral 6 and a deflected portion 7 forming a spout at one other end thereof.

Beneath what might be called the rear 85 end of the body are secured supporting members or feet 8 so as to hold this end raised off of a level support and pitch the bottom of the drain board forward when the spout extends over into the sink as seen 90 in Fig. 1; but the spout depends to a greater distance than the length of said feet, with the result that when the entire device is removed from the position shown in Fig. 1, where the spout hooks over the end of the 95 tubs into the sink, and laid on a level support, the spout will hold the front end of the device higher than the feet will support its rear end, and the water therein will drain in the opposite direction. 100

The deflected portion 7 or spout on the drain board extends downwardly and outwardly from the forward ends of the board at approximately an angle of 67 degrees while the flange 6 of the board is rolled outward to afford a hand hold for removing the board from the cover of a stationary tub or other flat support, and the rolls merge into the side edges of the deflected portion 7. 110

The grooves 9 in the body 5 which communicate at one end with the upper edge of the deflected portion 7 or spout diverge outwardly toward the rear end of the board 5 upon opposite sides of a centrally located groove extending longitudinally of the body 5 and coöperate with the upstanding flange 6 in preventing the sagging of the board under the weight of articles placed thereon 10 and also enable the greater portion of the water which is drained from said articles to be directed onto and substantially centrally of the deflected portion or spout 7 of the board and into a waste receptacle which in 15 this instance has been shown as the sink 2.

Through the arrangement of the supporting members and spout 7, it will be seen that if found desirable, the drain board may be placed upon a support, with the supporting 20 members and spout contacting therewith, so that the drain board will incline toward its flanged end and the water draining from articles placed thereon will be retained upon the board by the flange at the sides and ends 25 thereof.

The modified form of the invention is identical in construction with the preferred form of the invention with the exception that the rolled edge of the upstanding flange 30 6' has been eliminated in the construction shown in Fig. 5 of the drawing.

It will of course be understood that while the drain board has been described for use in connection with stationary wash tubs or 35 the like, it is not necessarily confined to this purpose, as its improved construction enables it to be used advantageously for various other purposes when desired.

For instance, if it should so happen that 40 there be no stationary tubs and no table immediately adjacent the sink, or that if they are, there they are in use at the time and therefore the housewife is called upon to drain her dishes on a table which may be a 45 little remote, the drain board is lifted bodily out of the position shown in Fig. 1 and placed upon the table top or other flat surface, when the relatively long spout lifts the open end of the board a little higher 50 than the relatively short feet raise the closed

or flanged end thereof. Then she washes and rinses her dishes as usual (in a dish pan which is in the sink or on a table adjacent the drain board) and places them one by one on the board to drain. The drainage water falls onto the bottom of the board and runs in the opposite direction from what it will in Fig. 1, and collects against the rear end flange at the closed end of the board. Finally she lifts the board with its 55 accumulated dishes and carries all to the sink, where she either tilts the board downward to pour the accumulated drainage water out over the spout or lays the board in the position shown in Fig. 1 if the top of the adjacent tubs or table have now been cleared and the space is therefore available. Thus this device, especially by the use of its 60 rolled side flanges which serve as handles, becomes not only a drain board but a tray 65 for carrying the dishes from point to point in case the need should arise.

It will also be understood that, while we have shown and described our improved drainboard as used for draining dishes in 70 the kitchen and adjacent the sink, it may obviously be employed for draining other articles without necessitating any change in its structure.

Having thus described the invention, what 75 is claimed as new is:

The herein described drain board substantially rectangular in contour and having flanges upstanding from its body along both sides and across one end, and rolled outward 80 at their upper edges, supporting feet depending from the bottom adjacent the flanged end, and a spout depending obliquely from the other end of the bottom to a greater extent than the length of said 85 feet, said flanges extending along the side edges of the spout, the whole for use substantially as described.

In testimony whereof we affix our signatures in presence of two witnesses.

AMOS BLISSMAN.
RICHARD E. STRUSE.
